UNITED STATES PATENT OFFICE.

ROBERT L. PATE, OF SPRINGFIELD, MISSOURI.

RADIATOR COVER.

Application filed January 24, 1924. Serial No. 688,337.

To all whom it may concern:

Be it known that I, ROBERT L. PATE, a citizen of the United States, residing at Springfield, Greene County, Missouri, have 5 invented a new and useful Radiator Cover, of which the following is a specification.

This invention relates to radiator covers for automobiles.

An object of the invention is to provide 10 a radiator cover comprising a plate supported stationarily in front of the radiator, an additional plate movable to different adjusted positions to cover or to expose different working areas of the radiator above the first plate, and means for guiding and retaining the movable plate in its adjusted positions.

Another object of the invention is to provide 15 a radiator cover embodying the structure last above mentioned and including also means designating the proper adjusted positions of the movable plate for different temperatures.

Another object of the invention is to provide 20 an improved radiator cover having a scale visible from the front of the radiator for indicating the proper adjusted positions of the movable cover plate for varying degrees of temperature, and means extending to the seating portion of the automobile for adjusting said plate, and provided also with 25 means for indicating proper adjusted positions of the plate for different temperatures.

Another object of the invention is to provide 30 a radiator cover comprising a permanently positioned plate covering the lower portion of the radiator and designed and adapted to display advertising and the like when exposed, in combination with another plate movable to and from a position in front of the lower plate to cover and to expose the lower plate, and designed and adapted also to bear advertising or other display matter and equipped with means for retaining it in different adjusted positions in front of the radiator.

Another object of the invention is to provide 35 a combined radiator cover and advertising display device of the character last above mentioned, and including also means for rendering the same visible at all times.

Other objects will appear from the following description, reference being made to the drawings, in which

Fig. 1 is a front elevation of the prefer-

red form of the present invention with parts 55 broken away to illustrate the relationship of the parts.

Fig. 2 is a vertical longitudinal sectional view.

Fig. 3 is a side elevation showing the 60 means extending to the seating portion of the automobile for adjusting and retaining the visible plate in its different positions.

Fig. 4 is a view showing a portion of the connection for adjusting the adjustable 65 plate bearing the indicating scale.

In the form of the invention shown there 70 are two guides for the adjustable plate of the radiator, one of said guides being supported vertically near each side of the radiator. Each guide, as shown, comprises a section or plate of metal bent or folded to provide a relatively wide portion 1 designed and adapted to rest against the front of the radiator, and an inwardly extended portion 2 75 spaced from the portion 1 and providing a vertical channel in which the movable plate of the radiator cover operates. The portion 1 of each guide is formed with a number of holes 3 intended to receive bolts 4 passing therethrough and through the radiator to support the guides in position. A sufficient number of the holes 3 are provided to assure that a proper number of bolts 4 may be passed through nearly any type of radiator 80 to which it may be desired to apply the invention, irrespective of the specific construction of the radiator.

The radiator cover shown comprises a lower stationary plate 5 having its ends 90 extending between the guides and the radiator and secured in position by the bolts 4 passing through the guides and the radiator, as stated. Preferably the plate 5 is made of a size to cover less than half of the front 95 of the radiator, thus adapting the device for use in warm weather as well as cold, since relatively a large portion of the working area of the radiator may be exposed by adjusting the movable plate in its lower adjustment in front of the plate 5.

The movable plate 6 is made of sufficient width to cover the entire working area of the radiator above the stationary plate 5, with the lower edge of the plate 6 extending 100 downwardly in front of the upper edge of the plate 5 in overlapping arrangement. The lower edge of the plate 6 may be formed

with a notch 7 of sufficient size to receive the crank 8 and the connection therefor, while the upper portion of the plate 5 may be provided with an upwardly extended portion 9 of sufficient size to close the space or notch 7 when the lower movable plate is raised.

Either or both of the plates may have advertising or other matter displayed thereon, all of which may be rendered visible at 10 all times by a lamp 10 supported above the radiator core and provided with a reflector 11 which properly confines and directs the light for best results. The light also renders visible a scale 12 on one of the guides 15 which indicates proper adjusted positions of the movable plate of the radiator cover for different temperatures, varying from the proper adjusted position thereof in relatively warm weather to the proper adjusted 20 position thereof in very cold weather.

If desired, a water cap may be provided above the radiator core in the form of a downwardly and forwardly inclined plate 13 to prevent water from entering the openings in the radiator.

To afford means for adjusting the upper plate of the radiator cover from the seating portion of the automobile, a flexible connection 14 from the plate 6 passes over the 30 radiator and into the seating portion of the automobile, where it is designed and adapted for engagement with a part 15 to support the plate 6 in different adjustments. For this purpose the connection 14 is provided with

35 holes 16 designated by scale characters 17 conforming to the scale 12. By this means the occupant of the automobile is enabled to adjust the plate 6 of the radiator cover from within the vehicle and without the necessity 40 of alighting. Instead of using the connection 14 extending to the seating portion of the automobile, a connection somewhat along the lines shown in Figs. 1 and 2 may be used, if desired. As there shown a flexible connection 18 from the plate 6 may be releasably engaged with a bracket 19 connected with the water inlet of the automobile and which may also serve as a support for the lamp 10 and its reflector 11.

50 If desired an additional plate 20 may be utilized to protect the rear or inner side of the radiator to the height of the plate 5. As shown (Fig. 2) the bolts 4, which secure the lower portions of the guides and which 55 hold the lower plate 5 in position, also pass through and retain the plate 20.

From the foregoing the utility and advantages of the invention are apparent, although it will be understood that the specific 60 construction and arrangement thereof may be varied within equivalent limits and within the scope of the appended claims without departure from the nature and principle of the invention. I do not restrict myself un-

essentially, but what I claim and desire to 65 secure by Letters Patent is:—

1. A radiator cover, comprising a vertical guide channel near each side of the radiator, removable elements passing through the radiator for supporting said guide channels 70 in position, a lower stationary cover plate having its ends between the guide channels and the radiator and retained in place thereby, a movable cover plate operative within the guide channels in front of the lower 75 plate and movable to positions to cover and to expose different portions of the working area of the radiator above the stationary plate, and means for supporting the movable plate in its different adjusted positions. 80

2. A radiator cover, comprising a pair of vertical guide channels, means for securing the guide channels in front of the radiator, a lower stationary cover plate having its ends between said guide channels and the radiator, an upwardly extended portion in connection with said stationary plate approximately midway between said guide channels, a movable cover plate operative within said guide channels in front of the 90 lower stationary plate and having a notch in its lower edge for the purpose mentioned and of a size to be closed by said upwardly extended portion of the stationary plate when the movable plate is in its upper adjustment, and means for supporting the movable plate in its various selected adjustments in said guide channels.

3. A radiator cover comprising a pair of separate and disconnected guide channels, 100 separate and independent supporting elements for supporting the guide channels in connection with the radiator, a stationary plate covering the lower portion of the front of the radiator, a movable plate operative within said guide channels for covering selected areas of the upper portion of the radiator above the stationary plate and having a notch in its lower edge receiving a vehicle member when said movable plate is in its lower adjustment, means for supporting the movable plate in its different adjusted positions, and means in connection with said first plate closing said notch when said movable plate is in its upper adjustments. 110 115

4. The combination with a radiator, of a pair of guide channels, one of which is near each side of the radiator, and each of which comprises a front wall and a rear wall, a lower stationary cover plate having its ends 120 extending between the radiator and the rear walls of said channels and thereby held against the front of the radiator, and a movable cover plate operative in said guide channels in front of said stationary plate and 125 spaced therefrom by the rear walls of said channels.

ROBERT L. PATE.
